UNITED STATES PATENT OFFICE.

CHARLES ALGERNON PARSONS, STANLEY SMITH COOK, AND EDWARD BROOKS CHAPMAN, OF WALLSEND-UPON-TYNE, ENGLAND; SAID COOK AND CHAPMAN ASSIGNORS TO SAID PARSONS.

MARINE-TURBINE INSTALLATION.

1,117,082.

Specification of Letters Patent. Patented Nov. 10, 1914.

Application filed December 9, 1913. Serial No. 805,589.

To all whom it may concern:

Be it known that we, CHARLES ALGERNON PARSONS, K. C. B., STANLEY SMITH COOK, and EDWARD BROOKS CHAPMAN, all subjects of the King of Great Britain and Ireland, and all residing at Turbinia Works, Wallsend-upon-Tyne, in the county of Northumberland, England, have invented certain new and useful Improvements in and Relating to Marine-Turbine Installations, of which the following is a specification.

This invention relates to marine turbine installations.

In such installations as, for instance, are suitable for war vessels, it is often necessary to design the machinery so as to operate efficiently under various speed conditions. Generally the highest degree of economy is desired at two conditions of service, one at the maximum power and speed of the vessel, and the other at a low cruising speed in order to give the vessel a large radius of action. As it is necessary to design the machinery for a large maximum power and speed, it usually results that only a moderate economy of fuel consumption is obtained at the cruising speed. The auxiliary machinery of the turbine installation is usually designed for the maximum power and speed conditions and the amount of steam required for this auxiliary machinery, even when operating under the low cruising speed conditions of the vessel, bears a very high ratio to the quantity of steam required for the turbine. Thus, to the steam consumption of the turbines at low powers has to be added the steam consumption of the auxiliary machinery which, as already stated, bears a high ratio to the steam consumption of the turbines. Thus the economy of the whole installation at the low cruising speed is further reduced.

The object of the present invention is to provide a marine turbine installation which will give the highest degree of efficiency of steam consumption by the machinery comprising the installation under both conditions of service.

The invention consists in a marine turbine installation having a main turbine system and an independently operable cruising turbine system the turbines comprising the

latter system driving propeller shaft or shafts through single reduction gearing. The main turbine system is designed so as to develop the maximum power required, and to propel the vessel at the maximum speed. This main turbine system may comprise any number of turbines coupled direct or through gearing to any number of propeller shafts. Astern turbines may also be provided in the main turbine system. Arrangements may also be made to connect the turbines forming the main turbine system in parallel or in series, or in any form of series parallel connection as may be desired. This main turbine system will also comprise the necessary auxiliary machinery, and is arranged to operate with the highest attainable degree of efficiency. If desired, the main turbine system may also comprise turbines additional to those which would be normally used to develop the maximum power and speed, such additional turbines being employed in series with the full power turbines at speeds intermediate between the maximum speed and the cruising speed at which the main turbine system would no longer operate and the cruising turbine system be utilized. The economy of the main turbine system at such intermediate speeds as above referred to may be increased by the introduction of high pressure action wheels or other means.

The cruising turbine system consists of a number of turbines of relatively small power driving some or all of the same propeller shafts as are driven by the main turbine system, being coupled to such shafts through mechanical or other forms of gearing, the difference of speed being effected by a single reduction. The turbines comprising the cruising turbine system are designed to obtain the highest degree of efficiency at the cruising speed. It may be arranged that such turbines are connected in series or in parallel or in series parallel, and that the mode of connection may be altered as desired. One or more astern turbines may also be provided in the cruising turbine system so that the maximum power available for going astern may be obtained, should necessity arise when cruising, from the boilers then under steam. The cruising turbine system may be provided with its own auxiliary

machinery, but as it is customary in war ships to provide auxiliary condensing plant for use in port such auxiliary condensing plant, may, if desired, be employed as the 5 condensing plant of the cruising turbine system.

The invention also consists in the improved marine turbine installations as herein described.

10 Referring now to the accompanying drawings:—Figure 1 represents a general plan view of an installation according to the present invention; Fig. 2 is an elevation of one of the center shafts, while Fig. 3 is an elevation 15 of one of the wing shafts; Figs. 4 and 5 are respectively end elevations of the cruising turbine system and main turbine system; Fig. 6 is a sectional view of gearing and clutching arrangement of the main and 20 cruising turbine systems. Figs. 7 and 8 show in elevation and plan respectively, the mechanism interlocking the clutches and valves of the installation; Figs. 9 and 10 are two part views of a valve showing the details 25 of the locking mechanism therefor.

The main turbine system and the cruising turbine system are so arranged that while the one system is operating the other is entirely disconnected from the propeller 30 shafting, suitable clutches being provided for this purpose. In the preferred arrangement the cruising turbine system is placed at the after end of the main turbine system and the gear wheel or wheels of the cruising 35 system are mounted on sleeves concentric with the propeller shaft or shafts and carried in suitable bearings. Clutches are arranged to connect or disconnect such sleeves to or from the propeller shafts and also to 40 disconnect or connect the main system driving shaft from or to such propeller shafts. A suitable thrust block is arranged on the propeller shaft so as to take the thrust of the propeller when either the main or the 45 cruising turbine systems are in operation. Clutches are also provided on such propeller shafts as are not driven by the cruising turbine system, so that the propellers which are idle while this system is in operation may 50 be free to revolve as they are dragged through the water. For safety in operation the means actuating the clutches are interlocked with the controlling valves of the two systems, so that it is impossible for 55 steam to be admitted to either system when uncoupled from its propeller shafts.

The astern turbine or turbines in the main and cruising turbine systems may be incorporated in the turbine or turbines of their 60 respective systems in the usual manner.

One particular installation having four propeller shafts according to this invention is as follows:—Each of the four propeller shafts, *a*, *b*, *c*, *d*, is driven by a separate main 65 turbine system, each of which systems com-

prises a high pressure turbine, *e*, an intermediate turbine, *f*, and two low pressure turbines, *g*, *h*, the latter receiving the steam in parallel from the intermediate pressure turbine. An astern turbine, *i*, is incorporated 70 with each of the said low pressure turbines, *g*, *h*. All the turbines in each main turbine system are geared to their respective main driving shaft, the gearing being contained within the casing indicated by the 75 reference letter, *j*. The main driving shaft of each main turbine system is indicated by the reference letter, *k*, and is connected in the case of the propeller shafts, *a* and *d*, through a clutch, *l*, and in the case of the 80 shafts, *b* and *c*, through a clutch, *L*. In the case of the center pair of shafts, *b* and *c*, a cruising turbine, *m*, is added to the turbines, *e*, *f*, *g*, *h*, comprising the main turbine system, this cruising turbine, *m*, being 85 utilized at speeds between the maximum and the cruising speed. Each main turbine system is provided with a condenser, *n*, which is situated immediately below the low pressure turbines, *g*, *h*, of that system. Each 90

main turbine system is arranged to develop the highest efficiency at the maximum power and speed of the vessel. It is also provided with its own auxiliary machinery, part of which is shown in the accompanying drawings. The center propeller shafts, *b*, *c*, are also arranged to be driven by a cruising turbine system, such a system comprising a high pressure turbine, *o*, an intermediate pressure turbine, *p*, and two low pressure turbines, *q*, *r*. With each of the two latter turbines there is incorporated an astern turbine, *s*. The high pressure turbine, *o*, and the low pressure turbine, *r*, are connected by 100 gearing, *t*, to a sleeve, *u*, mounted upon propeller shaft, *b*, to which it is connected by the clutch means *L*. Similarly the turbines, *p* and *q* are connected through gearing, *t*, to a sleeve, *u*, on the propeller shaft, *c*, to which it can also be connected by the clutch gear, *L*. The construction of the gearing, *t*, and the clutch, *L*, is more particularly described hereafter in reference to Fig. 6. The two low pressure turbines, *q* and *r*, of the cruising turbine system exhaust into a 110 common condenser, *v*, situated immediately below them. This condenser, *v*, is arranged to operate as part of the auxiliary condenser plant for use when the vessel is in port. The cruising turbine system is arranged to 115 develop the highest degree of efficiency at the cruising speed. A suitable thrust block, *w*, is provided on each of the propeller shafts, *a*, *b*, *c*, *d*, to absorb the propeller thrust. The clutches, *l*, provided in connection with the outer propeller shafts, *a* and *d*, allow these shafts to be disconnected from the shafts, *k*, of the main turbine system when the latter is not in operation.

In the drawings the details of the pipe 120

connections between the turbines and condenser and other gear are not, for the sake of clearness, completely illustrated.

One suitable form of clutch for use in this invention is shown in Fig. 6 which also indicates a construction of the gearing for the turbines of the cruising system. The drawing shows one of the center propeller shafts, for instance, *b*, and it will be seen that this is provided with two collars, *x* and *y*, in both of which teeth are formed. The driving shaft, *k*, of the main turbine system is also provided with a collar, *z*, in which teeth are formed. The collar, *y*, on the propeller shaft, *b*, and the collar, *z*, on the shaft, *k*, are adjacent to one another and are coupled or uncoupled according to the position of a clutch sleeve, 1, which is mounted in a ring, 2, pivotally attached to an arm, 3. The clutch sleeve, 1, is shown in full lines in the position in which the two collars, *y* and *z*, are uncoupled, while the dotted lines indicate the position of the sleeve when the two collars are coupled. The shaft of one of the cruising turbines is coupled to a pinion shaft, 4, which gears with the wheel, 5, built up upon a sleeve, 6, concentric upon the propeller shaft, *b*. The sleeve, 6, is provided with a collar, 7, which is adjacent to the collar, *x*, of the propeller shaft, *b*, and has similarly formed teeth in it. A clutch sleeve, 8, shown in full lines in the position connecting the two collars is mounted in a ring, 9, pivotally attached to the arm, 10. The dotted position of the sleeve, 8, is that in which the two collars, 7, and *x*, are disconnected. It will be seen that the relative positions of the clutch sleeves, 1 and 8 are such that when the main driving shaft, *k*, is disconnected 40 from the propeller shaft, *b*, the sleeve, 6, driven by the cruising turbine system is coupled to the propeller shaft, *b*. The clutch sleeves 1 and 8, being moved by the levers 10 and 3, which are connected by the link 45 39, move together so that when the sleeve, 6, is disconnected from the propeller shaft, *b*, the driving shaft, *k*, is coupled thereto, and vice versa.

The mechanism interlocking the clutch with the valves of the installation is shown in Figs. 7 and 8. It will be seen that the arm 14 by which the clutch sleeves are operated is provided with a portion of a worm wheel which carries a pin 41 which engages 50 with lever 39. The wheel 40 engages with a worm, 11, on a spindle, 12. The latter is connected by bevel wheels to a vertical spindle, 15, carrying at its upper end a bevel wheel, 16. The latter engages with bevel 55 wheels, 17, 18 respectively attached to spindles, 19 and 20. Engaging with the bevel wheels, 17 and 18, is a bevel wheel, 21, attached to a spindle, 22, on which is mounted a handwheel, 23. The spindle, 19, is provided with worms, 24, 25, in conjunction

respectively with the astern valve, 26, and the ahead valve, 27, admitting steam to the main turbine systems. The spindle, 20, is provided with worms 28, 42, in conjunction with the valve, 29, 43 admitting steam to the ahead cruising turbines and the astern cruising turbines respectively. The worms, 24, 25, 28 and 42, operate the locking mechanisms of their respective valves which will be more particularly described with reference to Figs. 9 and 10. These figures show the details of this locking gear attached to one of the valves, for instance, the valve, 26. It will be seen that the worm, 24, engages with a worm wheel, 30, which has a screw 80 thread engagement with a pin, 31. The worm wheel, 30, is mounted between abutments, 32, 33. Thus the rotation of the spindle, 19, causes the worm wheel, 30, to rotate and the screw thread engagement of this with the pin, 31, causes this pin to move in an axial direction.

As shown in Fig. 9 the pin, 31, in one extreme position enters holes in a pivoted segmental member, 34, which is provided with a portion of a worm wheel, 35, which engages with a worm, 36, on the spindle, 37, by which the valve is operated, thus the valve cannot be moved without a corresponding movement of the segmental member, 34, and if the movement of the latter be prevented by the pin, 31, it will be seen that the valve, 26, cannot be moved. The interlocking gear is so arranged that the relative positions of the pin 31, in respect 95 of each of the valves, 26, 27 and 29, with the astern valve, 26, and the head valve, 27, of the main turbine system can be moved while the cruising valve, 29, is locked or vice versa. The coupling of the spindles, 19 and 100 20, by the bevel wheels, 17 and 18 to the bevel wheel, 16, on the spindle, 15, prevents the locking or release of the valves, 26, 27, 29, without a corresponding movement of the 105 clutches. In this manner it is arranged that the steam cannot be admitted to the main turbine systems or to the cruising turbine system while these systems are disengaged from the propeller shaft, that is to say, steam can only be admitted to the main turbine systems or to the cruising turbine system when the corresponding clutches are engaged. The interlocking gear is also arranged so that the movement of the clutch member is completed before sufficient movement has been given to the pin, 31, to release the corresponding valve. 110

It will be seen that many modifications can be made in structure in carrying this invention into effect without in any way departing 115 from the spirit of the same.

Having now described our invention, what we claim as new and desire to secure by Letters Patent is:—

1. A marine turbine installation comprising—

ing a main turbine system, an independently operable cruising turbine system, a propeller shaft, single reduction gearing operating to connect said cruising turbine system to said propeller shaft.

2. A marine turbine installation comprising a main turbine system, a propeller shaft, clutch means between said main turbine system and said propeller shaft, an independently operable cruising turbine system, single reduction gearing between said cruising turbine system and said propeller shaft, and clutch means between said cruising turbine system and said gearing, 15 acting to connect and disconnect the same.

3. A marine turbine installation comprising a main turbine system, a propeller shaft, clutch means between said main turbine system and said propeller shaft, an independently operable cruising turbine system, single reduction gearing between said cruising turbine system and said propeller shaft, and clutch means between said 20 cruising turbine system and said gearing, 25 acting to connect and disconnect the same, and means interconnecting said clutch means and acting to prevent simultaneous connection of said main and cruising systems to said propeller shaft.

4. A marine turbine installation comprising a main turbine system, a propeller shaft, clutch means between said main turbine system and said propeller shaft, an independently operable cruising turbine system, single reduction gearing between said 30 cruising turbine system and said propeller shaft, and clutch means between said 35 cruising turbine system and said gearing, acting to connect and disconnect the same; a throttle

valve upon said main turbine system, a 40 throttle valve upon said cruising turbine system, and means between said throttle valves and said clutch means acting to interlock said clutch and throttle means, to prevent admission of steam to either turbine system when it is disconnected from the propeller shaft. 45

5. A marine turbine installation comprising a main turbine system, a cruising turbine system, a propeller shaft, clutch means 50 between said main and cruising turbines and said propeller shaft, throttle valves upon said turbine systems and interlocking means between said valves and clutches.

6. A marine turbine installation comprising a main turbine system, an independently operable cruising turbine system, condensing plant for the auxiliaries of said turbine installation, means whereby said cruising turbine system can discharge into said auxiliary condensing plant. 55

7. A marine turbine installation, comprising a propeller shaft, a main turbine system, single reduction gear operating to connect said main turbine system to said propeller 60 shaft, an independently operable cruising turbine system and single reduction gearing operating to connect said cruising turbine system to said propeller shaft. 65
